UNITED STATES PATENT OFFICE

2,608,950

THREAD WAXING DEVICE

Robert L. Bradley, Beverly, Mass., assignor to
 United Shoe Machinery Corporation, Flemington, N. J., a corporation of New Jersey

Application June 9, 1950, Serial No. 167,134

2 Claims. (Cl. 118—125)

1

The present invention relates to thread waxing devices for use with shoe sewing and thread winding machines and to improvements in strippers for waxing devices of the type disclosed in United States Letters Patent No. 1,015,772, granted January 30, 1912, upon application of Fred Ashworth, and in an application for United States Letters Patent Serial No. 86,349, filed April 8, 1949, now Patent No. 2,576,961, granted December 4, 1951, in the name of John F. McCarthy.

The stripper of the McCarthy patent is an improvement over that disclosed in the Ashworth patent and the improvement contributes substantially to the durability and ease in adjustment of the Ashworth stripper. It has been found, however, that in certain instances, particularly in starting a sewing or winding machine in operation, that small chunks of incompletely liquefied wax or solid particles of foreign materials may momentarily impede the thread in its passage through the stripper, such chunks or particles being carried along with the thread to the injury or excessive wear of the stripper. The stripper of the McCarthy patent comprises primarily a compressible perforated rubber plug through which the thread is drawn and in case chunks or particles of solid material are drawn into the perforation of the plug and become wedged therein, they may cause faulty stripping action on the thread.

It is an object of the present invention to reduce to a minimum the likelihood of injury to a wax stripper of a sewing or winding machine employing a compressible plug as the stripping element, with a view to increasing the durability of the stripping element and reducing the possibility of improper stripping action or injury to the thread acted upon, either momentarily or permanently from the presence of chunks, or particles of solid material, passing into the plug with the thread. Other objects of the invention are to improve the construction and simplify still further the effectiveness of adjustments during use of a wax thread stripper.

In accordance with these objects, a thread waxing device has been provided having a compressible perforated wax stripper plug, which is equipped with a prestripper for the thread located along the length of the thread at a point just before it enters the stripper plug, comprising a refractory bead formed with a loose fitting opening for the thread in line with the perforation in the plug and of a size to admit passage of a knot in the thread while limiting the amount of wax and the size of solid chunks or particles

carried into the compressible plug with the thread. The admission of a knot in the thread is highly desirable in the operation of a stripper plug in changing from one type of thread to another where different types of sewing work are to be performed or where wound packages of differently colored threads are to be prepared on the same winding machine.

These and other features of the invention as 10 hereinafter described and claimed will readily be understood from the following detailed description taken in connection with the accompanying drawings in which,

Fig. 1 is a sectional view on an enlarged scale 15 of a waxing device and an upper portion of a cover for a wax pot embodying the features of the present invention, and

Fig. 2 is a similar view on a further enlarged scale of a protecting bead and its mounting 20 through which thread passes to a stripper for the waxing device.

The illustrated thread waxing device is intended for use in connection with a wax pot, the cover portion of which is indicated at 4, through which 25 a thread 6 passes in the direction of the arrows in Fig. 1. The thread enters a tube 8 in the wax pot cover and after being submerged within a bath of liquid wax, either in a molten or emulsified state, the thread is drawn through a perforated compressible rubber stripper plug 10 supported within a split sleeve 12 mounted in turn within an internal seat in an externally threaded socket 14. To compress the plug against the 30 thread the upper end of the plug is engaged by a compressor 16 loosely mounted in an internally threaded cap 18 engaging the threads on the socket 14. The sleeve 12 is slidably mounted in the socket for easy removal and has its upper end open to receive the compressor 16. The sleeve 35 has a perforated wall at its lower end into which the thread enters. The ends of the plug 10 are formed with conical surfaces having substantially different conical angles, the end of the largest angle being at the bottom where the thread enters. In other respects the construction of the 40 thread waxing stripper is similar to that disclosed in the McCarthy patent.

In order to protect the internal surfaces of the 45 perforated rubber stripper plug 10 from injury due to the passage of particles of solid material along with the thread into the plug, it has been proposed to employ a refractory bead having an opening in line with the perforation of the plug at that end of the plug into which the thread enters. The use of such bead, however, if it fits

closely with the thread is objectionable when an attempt is made to rethread the waxing device through the common expedient of tying a knot between the end of the old thread supply and that of a new supply of thread. To require an operator to rethread the waxing device with a rethreading wire and manual insertion of the thread involves a highly disagreeable and tedious task which more than offsets the desirability of improving the durability of the stripper plug itself. 10

According to the present invention, by the use of a properly selected refractory bead the difficulties encountered in rethreading a waxing device of the type referred to have been overcome and substantial benefits have resulted in the direction of increasing the durability of the stripper plug. Accordingly, the lower thread entering end of the socket 14 is counterbored at 20 in line with the perforated end wall of the sleeve 12 and inserted within the counterbore is a refractory bead 22 having a loose fitting opening 24 for the thread also in line with the perforation in the plug and of a size approximately three times the compressed diameter of the thread. The purpose of the loose fitting opening is to admit passage of a knot in the thread when rethreading the waxing device. Such a knot is indicated at 26 (Fig. 2) joining the ends of an old supply of thread, unshaded to indicate white thread and a new supply, shaded to indicate colored thread. The opening 24 is of such size as will pass the knot 26 when the knot is tightened into a compressed condition, the knot having a close fit within the opening. A secondary advantage of the bead in the prescribed size of opening is that there is no danger of loosening the knot from frictional engagement with the surfaces inside the passage of the stripper plug 10, once having passed the bead. The large size of opening in the bead as compared with the compressed diameter of the thread has been found to be not without some substantial benefit in improving the durability of the stripper plug, and in actual use stripper plugs have lasted several times longer with a bead so located and constructed than without such bead. 40

The exact reason for improvement in durability of the life of a stripper plug when used with a bead of loose fitting opening is not clearly understood but such bead appears to contribute to the durability of the plug in several particulars. The bead being of refractory material serves to obstruct and break up particles of solid wax or foreign materials before they can enter the inner surfaces of the passage in the plug and the bead protects the plug from application of excessive pressures in the wax when the thread is drawn through rapidly with wax in viscous or semi-melted condition. In this respect a more uniform application of wax is made. Additional benefits from the bead are derived from the fact that no outlet exists between the bead and the thread entering end of the plug so that any pressure which is built up inside the thread entering end of the plug serves to impregnate the thread passing therethrough more deeply than otherwise would be possible. 55

The construction and arrangement of the bead 22 in the counterbore 20 is such that it is securely held in place close to the perforated lower end of the stripper plug and may readily be replaced when a substantial change in size of the thread 60

is to be made. For this purpose the lower end of the sleeve 12 bears directly against the bead and prevents displacement of the bead from the counterbore. The bead is easily accessible when the sleeve is removed. If the bead is slidably in the counterbore, which may be desirable, pressure against the bead may effect the compression of the plug by the compressor, the bead tending to raise the sleeve slightly in the socket 14. While such compression of the plug would not be continuous with the compressor in a condition of proper adjustment, a temporary increase in the compression such as occurs during passage of a knot or other obstruction would tend to eject excess quantities of wax from the passage in the plug so that the knot or other obstruction might pass through more easily when it reaches the thread-entering end of the plug, the compression of the plug by the bead then being relieved. 15

The nature and scope of the invention having been indicated and the particular embodiment having been described, what is claimed is:

1. A thread waxing device having a stripper sleeve formed with one end open and a perforated wall at the other end into which the thread enters, a socket within which the sleeve is disposed having a counterbored opening in line with the perforation in the end wall of the stripper sleeve, a compressible perforated wax stripper plug disposed in the stripper sleeve and a compressor acting at the open end of the sleeve on the stripper plug to secure the plug and sleeve within the socket, in combination with a refractory bead formed with an opening for the thread, mounted in the counterbore of the socket with its opening in line with the perforation in the plug and secured in place within the counterbore of the socket close to the perforated end of the stripper plug. 30
2. A thread waxing device having a stripper sleeve formed with one end open and a perforated wall at the other end into which the thread enters, a socket within which the sleeve is disposed having a counterbored opening in line with the perforation in the end wall of the stripper sleeve, a compressible perforated wax stripper plug disposed in the stripper sleeve and a compressor acting at the open end of the sleeve on the stripper plug to secure the plug and sleeve within the socket, in combination with a refractory bead slidably mounted in the counterbore of the socket in line with the perforated end wall of the sleeve and arranged to be secured in the counterbore by engagement with the perforated end of the sleeve, said refractory bead having a loose fitting opening for the thread of a size approximately three times the compressed diameter of the thread to admit passage of a knot in the thread while limiting the amount of wax carried through the bead into the compressible plug and to effect the compression of the plug against the compressor during passage of a knot through the bead. 35
